UNITED STATES PATENT OFFICE.

JOHN L. KELLOGG, OF BATTLE CREEK, MICHIGAN.

PROCESS OF MAKING CONFECTIONERY.

1,110,267.

Specification of Letters Patent. Patented Sept. 8, 1914.

Application filed December 10, 1913. Serial No. 805,795.

To all whom it may concern:

Be it known that I, JOHN L. KELLOGG, a citizen of the United States, residing at Battle Creek, Michigan, have invented certain new and useful Improvements in Processes of Making Confectionery, of which the following is a specification.

This invention relates to a new and improved process for making confectionery.

10 The object of this invention is to provide a process by means of which confectionery may be made from flaked cereals.

15 Further objects, and objects relating to details and economies of operation, will definitely appear from the detailed description to follow.

I accomplish the objects of my invention by the devices and means described in the following specification.

20 The invention is clearly defined and pointed out in the claims.

A machine in which I preferably carry out my invention is clearly illustrated in the accompanying drawing forming a part 25 of this specification, in which:

Figure I is a longitudinal sectional view through the machine on the line 1—1 of Fig. II. Fig. II is a sectional view taken on the line 2—2 of Fig. I. Fig. III is a 30 sectional view on the line 3—3 of Fig. II, showing one end of the wire cloth cylinder in detail. Fig. IV is a detail view showing a portion of the perforated steam pipe. Fig. V is a perspective view of a brick of 35 the finished product.

In the drawing, similar reference characters refer to similar parts throughout the several views, and the sectional views are taken looking in the direction of the little 40 arrows at the ends of the section lines.

Considering the numbered parts of the drawing, 1 indicates the cylindrical casing which is provided with ends 2, and suitably supported in frame 3. This casing is 45 provided with an opening 4 at the top, closed by a cover 5, through which opening the materials may be delivered into the machine. A second opening 6 is provided at the bottom of the casing through which the 50 material is discharged from the machine. Secured in the bottom of the casing is a steam pipe 7 which is provided with a plurality of perforations 8 on its upper face through which steam is ejected in small jets 55 into the interior of the casing. A shaft 11 suitably journaled in the ends of the casing

carries upon it the cylinder 9 which is provided with an opening 13 for filling the same and upon the outer end of the shaft 11 is provided a pulley 12 by means of which power may be applied to the shaft to rotate it. Cylinder 9 is perforated and may be made out of perforated metal or, preferably, out of wire cloth.

In carrying out my process, I fill the perforated cylinder with a quantity of ordinary toasted flakes of corn or wheat. Steam is admitted through the pipe 7 and issues in small jets through the perforations therein, passing up through the cylinder and its contents. The cylinder is caused to rotate slowly so that the steam strikes the flakes uniformly and all of them take up practically the same amount of moisture. This is continued for a considerable time, until the flakes have taken up such an amount of moisture that they are no longer brittle but are tough and tenacious. When this state has been reached the cylinder is stopped and powdered candy is poured into it, gradually mixing through the entire mass. After the powdered candy is poured into the cylinder, the cylinder is started rotating again, and steam is admitted through the pipe 7 issuing in small jets and passing up through the cylinder and the agitated contents thereof, thus further exposing the contents of the cylinder to the action of jets of steam. The heat from the steam and the moisture causes the fine particles of candy to melt and liquefy and the flakes are covered with a very thin coating of liquid candy. Inasmuch as the cylinder is constantly turning, every particle is thoroughly and uniformly coated with this candy.

As soon as the flakes have been thoroughly coated the cylinder is stopped and the contents are discharged through the bottom opening of the casing. On account of the moisture to which the flakes have been exposed, they are very tough and tenacious and can easily be molded into any shape. While the product is still moist and tough it is molded in presses into bricks of any desired size and shape, and these bricks are 105 then placed on tin or paraffined cardboard trays, and dried by circulating either hot or cold air around them. After these bricks have been thoroughly dried the confection is ready to put up in packages.

110 It is to be noted that any form of flaked or shredded cereal may be used for this proc-

ess so long as it is toughened by the action of moisture. However the flakes are to be preferred in view of the fact that they present a greater surface to the action of the steam and the liquid candy. It will also be noted that any form of candy, sugar, or other saccharine material which can be powdered, may be used to furnish the candy coating.

10 Having thus described my invention, what I claim as new and desire to secure by Letters Patent is:

1. The process of making confections consisting in exposing shredded or flaked cereal, while such material is being agitated, to the action of jets of steam, adding powdered saccharine material thereto, further exposing the mixture to the action of jets of steam, molding said material into bricks of suitable shape and size and drying said bricks.

2. The process of making confections consisting in exposing shredded or flaked cereal, while such material is being agitated, to the action of jets of steam, adding powdered saccharine material to said shredded or flaked cereal, further exposing the mixture to the action of jets of steam and molding said material into bricks of suitable shape and size.

30 3. The process of making confections consisting in exposing shredded or flaked cereal, while such material is being agitated, to the action of jets of steam, adding saccharine material thereto, and further exposing the mixture to the action of jets of steam.

35 4. The process of making confections, consisting in exposing flaked or shredded cereal to the action of steam, mixing powdered saccharine material with said cereal, further ex-

posing the mixture to the action of steam, 40 molding the product into bricks of any desired shape or size, and drying said bricks.

5. The process of making confections, consisting in exposing flakes or shredded cereal to the action of steam, mixing powdered saccharine material with said cereal, and further exposing the mixture to the action of steam.

6. The process of making confections, consisting in causing flaked or shredded cereal 50 to take up moisture slowly, and uniformly, mixing powdered saccharine material with said cereal, exposing the mixture to the action of steam, molding the product into bricks of any desired shape or size, and dry- 55 ing said bricks.

7. The process of making confections, consisting in causing flaked or shredded cereal to take up moisture slowly, and uniformly, mixing powdered saccharine material with 60 said cereal, and exposing the mixture to the action of steam.

8. The process of making confections, consisting in exposing flaked or shredded cereal to the action of steam, mixing powdered 65 saccharine material with said cereal, further exposing the mixture to the action of steam, said flaked or shredded cereal being constantly agitated during said operation, substantially as described for the purpose speci- 70 fied.

In witness whereof, I have hereunto set my hand and seal in the presence of two witnesses.

JOHN L. KELLOGG. [L. S.]
